(57) **CLAIM**

The ornamental design for a part of battery, as shown and described.

DESCRIPTION

FIG. 1 is a perspective view of a part of battery according to a first embodiment of the present design;

FIG. 2 is another perspective view of the part of battery according to a first embodiment of the present design;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a reference view thereof;

FIG. 10 is a perspective view of a part of battery according to a second embodiment of the present design;

FIG. 11 is another perspective view of the part of battery according to a second embodiment of the present design;

FIG. 12 is a front view thereof;

FIG. 13 is a rear view thereof;

FIG. 14 is a left side view thereof;

FIG. 15 is a right side view thereof;

FIG. 16 is a top view thereof;

FIG. 17 is a bottom view thereof;

FIG. 18 is a reference view thereof;

FIG. 19 is a perspective view of a part of battery according to a third embodiment of the present design;

FIG. 20 is another perspective view of the part of battery according to a third embodiment of the present design;

FIG. 21 is a front view thereof;

FIG. 22 is a rear view thereof;

FIG. 23 is a left side view thereof;

FIG. 24 is a right side view thereof;

FIG. 25 is a top view thereof;
